UNITED STATES PATENT OFFICE.

FREDERICK R. M. CUTCHEON, OF ST. PAUL, MINNESOTA.

CURRENT-REGULATOR FOR ELECTRIC TRANSFORMERS.

SPECIFICATION forming part of Letters Patent No. 693,841, dated February 25, 1902.

Application filed October 12, 1901. Serial No. 78,419. (No model.)

To all whom it may concern:

Be it known that I, FREDERICK R. M. CUTCHEON, a citizen of the United States, residing at St. Paul, in the county of Ramsey and State 5 of Minnesota, have invented certain new and useful Improvements in Current-Regulators for Electric Transformers; and I do hereby declare the following to be a full, clear, and exact description of the invention, such as will 10 enable others skilled in the art to which it appertains to make and use the same.

My present invention has for its especial object to provide an improved amperage or current regulator for series-arc-lamp systems; 15 and to the above ends the invention consists of the novel devices and combinations of devices hereinafter described, and defined in the claims.

The invention is illustrated in the accompanying drawings, wherein like characters indicate like parts throughout these several views.

Figure 1 is a view, principally in vertical section, showing an alternating transformer equipped with my improved regulator. Fig. 25 2 is a horizontal section on the line $x^2 x^2$ of Fig. 1, and Fig. 3 is a diagram illustrating the manner of connecting the transformer to the secondary or arc-light circuit.

The numeral 1 indicates a U-shaped laminated iron core, the same, as shown, being supported by an insulating-base 2 and having its prongs connected by a suitable insulating-plate, such as a marble slab 3.

The primary coil 4 is wound on the yoke of 35 the core 1 and, as shown, extends to binding-posts 5. The primary leads 6 are connected one to each of the binding-posts 5.

The secondary coil 7 is wound on both prongs of the core 1. In the best form of the 40 device this secondary coil is wound in sections, which are spaced apart and connected in series, as best shown in Fig. 1. As shown, the ends of the secondary coil 7 connect to binding-posts 8 on the slab or plate 3. The 45 leads 9 of the secondary circuit connect one to each of the binding-posts 8.

In the secondary circuit 9 is a series of arc-lamps 10, adapted to be connected in series or to be cut out of action by the ordinary or 50 any suitable switches 11.

A soft-iron bar or armature 12 works adjustably in the field of the secondary coil 7.

The said armature is conveniently guided by a pair of brass rods 13, secured at their upper ends to the slab 3 and at their lower ends 55 to a plate 14, suitably held between the prongs of the core 1.

The core 12 is adapted to be adjusted and to be held where set by suitable devices—such, for instance, as illustrated in the drawings.

15 indicates a sheave mounted in a bearing 16, secured on the slab 3.

17 indicates a cord or flexible band which works through a suitable slot 18 in the slab 3 65 and the lower end of which is connected to the armature or bar 12, while the upper end thereof is secured to the sheave 15. The sheave 15 is adapted to be moved by a hand piece or crank 19, and it is adapted to be set 70 in any one of five positions by means of a pin 20, which is adapted to be inserted through any one of five holes 21 in said sheave and into a suitable seat in the bearing-bracket 16.

The device illustrated in the drawings is 75 shown as designed for a five-light secondary circuit; but it will of course be understood that in practice the capacity of the device will be increased to meet the requirements of operative systems wherein a very large number 80 of lamps—usually about fifty—are connected in series and in common circuit.

For the purposes of illustration we will assume that each arc-lamp will require seventy-four volts and seven amperes and that each 85 section of the secondary coil 7 is capable of inducing a current of thirty-seven volts and seven amperes. Under these conditions since the horizontally opposite sections of the secondary coil are cut into and out of action 90 in pairs by the armature 12 it follows that there should be at least as many pairs of coil-sections in the secondary as there are lamps in the secondary circuit. It also follows that the said armature 12 should be so 95 adjusted as to cut into action below the same as many pairs of coil-sections as there are lamps thrown into action or connected in the secondary circuit. For instance, if but two lamps are thrown into action the armature 100 should be adjusted as shown in Fig. 1. When thus adjusted, the said armature short-circuits the magnetic field above the two lower pairs of coil-sections. The two pairs of coils

thus thrown into action will produce a current of one hundred and forty-eight volts and seven amperes, which is the current desired to run two arc-lamps in series.

5 If five lamps are thrown into action or connected in series in the secondary circuit, the armature 12 should be adjusted to the position indicated by dotted lines in Fig. 1, in which position the five pairs of coil-sections 10 will produce a current of three hundred and seventy volts and seven amperes, which is the current desired to run five lamps connected in series. As is evident, by properly adjusting the armature the voltage or potential may 15 be changed at will, while the amperage is maintained constant.

The device is of course capable of many modifications within the scope of my invention. While I consider the peculiarly-wound 20 secondary coil as novel and desire to claim the same, it would be within the scope of my invention to wind the secondary coil continuously or without dividing the same into sections. For some work it might be possible 25 to use what I have described as the secondary coil for the primary coil and to use what is herein illustrated as the primary coil as the secondary coil. It will also be understood that this device is not limited to use in connection 30 with arc-lamp systems, but is capable of general use wherever a device of this character may be found serviceable.

What I claim, and desire to secure by Letters Patent of the United States, is as follows:

35 1. The combination with the primary and secondary of an electric transformer, of an adjustable armature or bar arranged to variably short-circuit the magnetic field and to 40 cut into and out of action more or less of the

component parts of said secondary coil, substantially as described.

2. In an electric transformer, the combination with a U-shaped core, of a primary coil wound on the yoke of said core, a secondary coil wound on the prongs of said core, and an adjustable armature or bar working in the field of said secondary coil and serving to magnetically short-circuit the field of the secondary coil, and, by adjustment, to vary 45 50 the strength of the said secondary coil, substantially as described.

3. In an electric transformer, the combination with a core, of a primary and secondary coil wound thereon, said secondary being 55 formed by spaced sections, and an adjustable armature or bar working in the field of said primary coil and adapted to magnetically short-circuit the field of the primary coil and cut into and out of action more or less of the 60 sections of said secondary, substantially as described.

4. In an electric transformer the combination with a U-shaped core, of a primary coil wound on the yoke thereof, a secondary coil 65 wound in spaced sections on the prongs of said core, the sections on the two prongs being located in transversely opposite pairs, and an armature or bar working adjustably in the magnetic field of said secondary coil, for magnetically short-circuiting the said field, and adapted by adjustment, to cut into and out 70 of action more or less of the said coil-sections, substantially as described.

In testimony whereof I affix my signature 75 in presence of two witnesses.

FREDERICK R. M. CUTCHEON.
